(57) **CLAIM**

The ornamental design for a vehicle license plate frame having a pair of bumpers and vertical rods, as shown and described.

DESCRIPTION

FIG. 1 is a front elevational view of a vehicle license plate frame having a pair of bumpers and vertical rods showing my new design;

FIG. 2 is a rear elevational view thereof;

FIG. 3 is a top plan view thereof;

FIG. 4 is a bottom plan view thereof; and

FIG. 5 is a right side view thereof, the left side view being a mirror image.

The rods are shown broken away in FIGS. 1,2 and 5 to indicate indeterminate length.
